UNITED STATES PATENT OFFICE.

WALTER I. BROWNE, OF BRISTOL, VERMONT, ASSIGNOR OF ONE-HALF TO FRANK J. BRADY, OF MONTREAL, QUEBEC, CANADA.

AUTOMATIC TRAIN-PIPE COUPLING.

1,209,547.

Specification of Letters Patent.

Patented Dec. 19, 1916.

Application filed December 16, 1915. Serial No. 67,260.

To all whom it may concern:

Be it known that I, WALTER I. BROWNE, a citizen of the United States of America, residing at Bristol, State of Vermont, United States of America, have invented certain new and useful Improvements in Automatic Train-Pipe Couplings; and I do hereby declare that the following is a full, clear, and exact description of the invention, such as will enable others skilled in the art to which it appertains to make and use the same.

My invention relates to train pipe couplings.

The object of my invention is to provide a coupling device which will automatically become connected by the act of bringing the ends of two cars together.

A further specific object is to provide a construction which will adapt itself to the movement of the train to which it is attached and which will remain locked in operative position, at the same time permitting vertical and horizontal play following the movement of the adjacent ends of the cars to which it is attached, at the same time means being provided to limit this movement.

A further specific object is to provide means for guiding the parts into locked position as they come together and to provide an unlocking means which will work automatically when the ends of the cars are sufficiently separated.

My invention consists of the construction, combination and arrangement of parts, as herein illustrated, described and claimed.

In the accompanying drawings forming part hereof, I have illustrated a form of embodiment of my invention, in which drawings similar reference characters designate corresponding parts and in which:

Figure 1 is a detail side elevation of a car having the invention applied thereto; Fig. 2 is a broken detail end elevation of the car showing the invention in elevation; Fig. 3 is a vertical section through one of the connecting pipes; Fig. 4 is a detail horizontal section through another one of the connecting pipes; Fig. 5 is a detail section taken on the line 5—5 of Fig. 1; and, Fig. 6 is a vertical section through the coupler.

Referring to the drawings, 1 designates a car having a common form of train pipe 2, provided with the usual valve 3. An elbow 4 is secured to the train pipe 2 and supports

a horizontal length of pipe 5, which extends laterally approximately to the center of the car. This pipe 5 is mounted within bearings supported from the car frame by means of the brackets 5'. An elbow 6 is secured to the end of the pipe 5 to receive a vertical casing 7 (see Fig. 3). Slidably disposed in the casing 7 is a pipe 8 provided with flanges 9 at its upper end to receive packing 10. This construction permits a vertical movement equal to the distance between the lower flange 9 and the flange 7a of the casing, and also permits a swinging horizontal movement within certain limits, hereinafter described. An elbow 11 is secured to the lower end of the pipe 8 and has firmly attached to its forward end the horizontally disposed casing 12, which is provided with a longitudinal interior groove or way 13, to receive a spline 14 formed on the outside of a horizontally disposed pipe 15, which is disposed to slide within the casing 12. This construction permits a horizontal play, longitudinally of the car 1, and the spline and groove construction prevents axial movement of the coupling proper with respect to the pipe 8. Carried by the pipe 15 is a flared shell or head 16. The free end of the head is provided with an inclined surface or face 17, which is arranged to ride upon a similar face 85 on the corresponding coupling on another car to guide the parts into locking position, which corresponding coupling on the other car must be arranged in an inverted position with respect to the coupling as shown in 90 the drawings so that the two corresponding couplings when coming together will be readily coupled. Whereas in the drawings I have shown the coupling head arranged at one end of the car having its open face upward it 95 is, of course, to be understood that the coupling arranged at the opposite end of the car must be in a position so that its open face will extend downward so that when the two opposing coupling heads contact each other they will be automatically and properly coupled. The head 16 is provided with a passage 18 leading from the pipe 15 and terminating in a packing seat 19, so that a fluid tight joint is formed when two coupling 100 heads are brought into locked position. On one side of the head 16 there is formed a rounded wall 20, and on the opposite side is formed a boss 21, conforming in contour to the wall 20, so that when two similar cou- 105

pling heads are brought together the bosses 21 fit into the rounded walls 20 and the passages 18 register.

The boss 21 is formed with a shoulder 22 arranged to coöperate with the pointed end of a plunger 23, when two coupling heads are brought together as described. The plunger 23 is arranged to pass through a bore 24 having an inclined wall 24' and formed through one side of the shell or head 16. The plunger 23 is provided with a bore 25, to receive a guide rod 26, which is disposed in a casing 27 secured on one side of the head 16. A spring 28 maintains the plunger 23 in its position projecting through the bore 24. In case the connection is to be broken by the separation of adjacent cars, the force is sufficient for the shoulder 22 to bear upon the pointed end of the plunger 23 and force its inclined face 23' against the inclined face 24' of the bore 24 and to force the plunger downward and into the casing 27 to unlock the head. The spring 26 on the rod 26 returns the plunger 23 to its normal position, assisted by the tension of the spring 28.

To facilitate the interlocking of two coupler heads constructed as described, the boss 21 is provided with an under cut beveled surface 29 forming an interlocking element for the head 16. Horizontal movement of the casing 12 is limited by means of a brace 30 secured on the bearing supported by the bracket 5' or adjacent part of the car 1, and a loop 31 carried on the lower end of the brace, extending around the casing 12 and connected thereto by coiled springs 32 or similar resilient members thereby permitting a slight longitudinal movement with respect to the car but the coiled springs provide means for returning the same to its normal position and also prevent any axial movement of the coupler.

Copies of this patent may be obtained for five cents each, by addressing the "Commissioner of Patents, Washington, D. C."

As each end of the car is to be equipped with a coupler head of the construction described I have described only one coupler head, it being understood that the construction at both ends of the car is identical.

Having thus fully described my invention, what I claim as new and desire to secure by Letters Patent is:

1. A train pipe coupling comprising an interlockable head having a boss formed with a shoulder, a casing disposed on the head, a plunger having a pointed end projecting through an opening provided in the head and having an inclined wall, a spring under the plunger, a rod disposed transversely through the plunger and a spring on the rod. 55

2. A train pipe coupling comprising an interlockable head, a longitudinally adjustable pipe connected to one end of said head, a vertically adjustable pipe connected to the opposite end of said longitudinally arranged pipe, a support, and coil springs 65 connecting said longitudinally adjustable pipe to said support substantially as and for the purpose specified.

3. A train pipe coupling comprising a coupling head, said coupling head comprising a flared semicircular portion, a boss formed with said head and provided with a shoulder, a casing secured to said flared semicircular portion, a spring actuated plunger arranged within said casing and adapted 75 to normally project within said flared semicircular portion, and the opposite walls of said plunger being inclined substantially as and for the purpose specified.

In witness whereof I have hereunto set 80 my hand in the presence of two witnesses.

WALTER I. BROWNE.
